US0D1078638S

(12) **United States Design Patent** (10) **Patent No.:** **US D1,078,638 S**
(45) **Date of Patent:** **** Jun. 10, 2025**

(54) **VARIABLE FREQUENCY CONTROL DEVICE**

(71) Applicant: **Weifang Xingyuan Trading Co., Ltd.**,
Weifang (CN)

(72) Inventor: **Yangyang Chen**, Shuangyashan (CN)

(73) Assignee: **Weifang Xingyuan Trading Co., Ltd.**,
Weifang (CN)

(**) Term: **15 Years**

(21) Appl. No.: **29/982,741**

(22) Filed: **Jan. 7, 2025**

(51) LOC (15) Cl. **13-02**

(52) U.S. Cl.

USPC **D13/123; D13/133**

(58) **Field of Classification Search**

USPC D13/123, 103, 104, 107, 108, 110, 112,
D13/116, 118, 119, 184, 199, 146, 154,
D13/133

CPC H02J 7/0044; H02J 7/0042; H02J 7/0045;
H02J 7/0047; H02J 7/00

(57) **CLAIM**

The ornamental design for a variable frequency control device, as shown and described.

DESCRIPTION

FIG. 1 is a top, front, right side perspective view of a variable frequency control device, showing my new design; FIG. 2 is a bottom, rear, left side perspective view thereof; FIG. 3 is a top, front perspective view thereof; FIG. 4 is a front elevational view thereof; FIG. 5 is a rear elevational view thereof; FIG. 6 is a left side elevational view thereof; FIG. 7 is a right side elevational view thereof; FIG. 8 is a top plan view thereof; FIG. 9 is a bottom plan view thereof;

FIG. 10 is an enlarged view of portion 10 in FIG. 1; FIG. 11 is an enlarged view of portion 11 in FIG. 1; FIG. 12 is an enlarged view of portion 12 in FIG. 2; FIG. 13 is an enlarged view of portion 13 in FIG. 3; and, FIG. 14 is an enlarged view of portion 14 in FIG. 8.

The evenly dashed broken lines illustrate portions of the variable frequency control device and form no part of the claimed design. The unevenly dashed broken lines define the boundaries of enlarged views and form no part of the claimed design.

1 Claim, 14 Drawing Sheets
